[57] CLAIM

The ornamental design for a welding hood lens support, as shown and described.

DESCRIPTION

FIG. 1 is a front perspective view of a welding hood lens support showing my new design, the broken line illustration of welding hood is for illustrative purposes only and forms no part of the claimed design;

FIG. 2 is a rear elevational view thereof;

FIG. 3 is a front elevational view thereof;

FIG. 4 is a side elevational view thereof with the lens raised;

FIG. 5 is a side elevational view with the lens lowered;

FIG. 6 is a top plan view thereof;

FIG. 7 is a bottom plan view thereof;

FIG. 8 is a front top perspective view thereof; and

FIG. 9 is a rear top perspective view thereof.

FIG. 8

FIG. 9
